CIGAR AND CIGARETTE LIGHTING CONTAINER

Filed Sept. 17, 1925

FIG. 1.

FIG. 2.

FIG. 3.

Inventor

R. H. Doak

By *A. Randolph Jr.* Attorney

UNITED STATES PATENT OFFICE.

BURRELL H. DOAK, OF PINE BLUFF, ARKANSAS.

CIGAR AND CIGARETTE LIGHTING CONTAINER.

Application filed September 17, 1925. Serial No. 56,977.

The invention relates to individual containers for cigars and cigarettes and has for its object the provision of a two-part container to cover a cigar or a cigarette to prevent it from being broken by carrying it in the pocket and has for its object the provision of such a container made of paper of reasonably heavy quality and comprising two members one slightly larger in diameter than the other to permit telescoping of one into the other to form a complete container.

Another object of the invention is the provision of means on the two parts of the container to ignite one of the parts of the container to be used as a match to light the contents of the container.

The construction and advantages of the invention will be described in detail hereinafter and will be found illustrated in the accompanying drawings, in which

Figure 1 is a side view in elevation of the container assembled,

Figure 2 a longitudinal sectional view showing a cigar in position in the container, and

Figure 3 a view of one of the ends of the container.

In the drawings similar reference characters will be used to designate corresponding parts throughout the several views.

The improved container comprises two members designated 1 and 2, respectively, the member 1 being slightly larger in diameter than the member 2 so that its open end will slip over and frictionally engage the open end of member 2 when a cigar is in position therein and serves to protect the cigar from or breaking incidental to carrying the cigar in the pocket.

The members 1 and 2 are formed of paper of reasonably heavy stock to make the container of sufficient rigidity to reinforce the cigar and protect it from breakage in ordinary handling and carrying in the pocket.

The ends of the parts 1 and 2 are closed and part 1 has thereon a chemical usually found on the head of a safety match, such for instance as potassium chlorate and antimony

sulfid, designated 3, while on the end of the receptacle 2 will be placed the usual ingredients of the striking surface of a safety match box containing phosphorus, this being designated at 4. By the provision of the parts 3 and 4 it will be understood that the smoker after removing the cigar from the container may light it by striking 3 on 4 and igniting the receptacle 1, thus utilizing the receptacle not only as a container but also as an igniter for the cigar contained within the container.

While the device has been illustrated in the drawings in connection with cigars, it will be apparent that by reducing the diameter of the container it may be utilized for holding single cigarettes for the same purpose that the device used for holding the cigar, and furthermore that the end of the container may be provided with means for igniting the container to utilize it as a match when desired by the smoker. It will also be apparent that the cigar container may be made of varying diameters to accommodate cigars of different diameters and that the two parts of the container may be made of sufficient length to accommodate cigars of different lengths or if desired that the container may be made of any size found desirable for the purpose to which it is to be put.

What is claimed is:—

An individual container for cigars and cigarettes, comprising a paper container sufficiently rigid to reinforce its contents, said container consisting of two hollow members closed at one of their ends and telescopically engaging one another at their open ends, a strip of chemical composition on the end of the inner member and covered by the outer member when the container is closed, and another strip of chemical on the closed end of the outer member that will ignite said member when rubbed on the first mentioned strip.

In testimony whereof I affix my signature.

RUSSELL H. DOAK.
